ATTORNEY

UNITED STATES PATENT OFFICE.

EDWARD L. HEYDECKER, OF NEW YORK, N. Y.

BOOK.

SPECIFICATION forming part of Letters Patent No. 634,265, dated October 3, 1899.

Application filed May 11, 1899. Serial No. 716,337. (No model.)

To all whom it may concern:

Be it known that I, EDWARD L. HEYDECKER, a citizen of the United States, and a resident of the city of New York, borough of Manhattan, county of New York, and State of New York, have invented certain new and useful Improvements in Books, of which the following is a specification, reference being had to the accompanying drawings, forming part hereof.

This invention relates to books, and has for its objects to provide for the amendment of books already printed and bound in such manner as to produce a practically new book without any portions therein of the parts it is desired to omit and to provide binding means whereby a satisfactory separable book may be produced capable of being taken apart for the removal or insertion of leaves at any parts thereof and yet a satisfactory book for handling and using, resembling closely in appearance an ordinary permanently-bound book.

My invention includes various improvements in separable books and temporary binders, including a movable connection between the holding means and cover, whereby in the ordinary movements of the cover the clamping devices of the holding means are covered or concealed; but by reason of this movable connection a small additional movement permits access to these clamping devices for the purpose of taking the book apart.

My invention has other objects and advantageous features and includes various improvements, all of which will now be particularly described with reference to the accompanying drawings.

Figure 1 is a transverse section on a plane indicated by the line 22, Fig. 3, but with the book closed, of a separable book embodying my invention. Fig. 2 is a similar view, but with the upper cover open and moved rearwardly, so as to permit access to the clamping devices. Fig. 3 is a plan view of the book as shown in Fig. 2.

The holder shown includes a front clamping-bar 4 and a rear clamping-bar 5 and binding-pins 6, and the binding-pins may be secured to one of the clamping-bars and are

shown as secured to the front clamping-bar 4. The leaves 7 are preferably separate sheets and are suitably perforated near their back edges and placed over the binding-pins 6, and they are clamped together by clamping devices or nuts 8, which are screwed over the clamping-pins 6 and bear upon the rear clamping-bar 5. The number of binding-pins may be varied for different sizes of books, three binding-pins being most frequently employed. The covers 9 and 10 are hinged to the holder at the front edges of the clamping-bars, so as to be angularly movable relatively to the holder. One of the covers, 15 and as shown the front cover 9, has a simple hinge connection with the corresponding clamping-bar, such connection being shown as formed by the hinges 11, of which one is shown, formed partly by lugs extending forwardly from the clamping-bar 4 and partly by a lug extending rearwardly from the hinge-bar 12, the hinge-bar 12 being secured to the front cover by a bent staple or clasp 13 and passing between the two boards forming the 20 cover. The other cover (shown as the rear cover 10) has a hinge connection with the corresponding clamping-bar 5 and is also movably connected thereto, so that it may be moved rearwardly to permit access to the 25 clamping devices, the hinge connection being shown as formed by the hinges 14, of which one is shown, each partly formed by the hinge-bar 15 and corresponding to the hinges 11; but the hinge-bar 15 has a sliding connection with the cover, shown as formed by the bent staple or clasp 16, to permit the above-described movement of the cover. The sliding hinge-bar 15 is of uniform width in the parts which move through the clasp 16, 30 but increases in width, so as to form a shoulder 17 at the point where it is desirable to arrest its sliding movement. The number of hinges at the front and back of the book may be varied for different sizes of books, two 35 hinges at the front and two hinges at the back being most frequently employed.

The flexible back 18 of the book is shown as secured to the covers, and may be secured thereto in any usual or desired manner. 40 Should it be desired to attain the usual rounded appearance of the back of an ordi-

nary book, this back may be padded or may have a wooden or leather block inserted therein in any well-known manner.

In the ordinary use of the book the sliding hinge-bars 15 will be pushed in to their full extent, as shown in Fig. 1, and the covers will open on the hinges 11 and 14 in about the same positions as the covers of an ordinarily-bound book, and the book will not materially differ in appearance from an ordinary book. Only the front edges of the clamping-bars will be visible, and the clamping devices or nuts will be covered and entirely concealed. When, however, it is desired to amend the book, the cover having the movable connection is opened and then pulled rearwardly to the position shown in Fig. 2, and thereby the clamping-bar and clamping-nuts will be completely uncovered, and the clamping-nuts 20 will now be readily accessible and may be unscrewed and the clamping-bar lifted off from the binding-pins and all or any number of the leaves taken out and new leaves inserted, as may be desired. At the conclusion of this 25 operation the rear cover may be pushed forward to the hinges and the book thus restored to its normal condition.

It will be evident that the devices embodying my invention are well adapted either for 30 permanent or temporary binders. The binding-pins 6 may not be secured to the front clamping-bars 4, so that the binding-pins may be removed, when desired, and other binding-pins of different length substituted therefor. Should it be desired to take the book apart from its front, then the threaded ends of the binding-pins and the clamping-nuts thereon would be at the front of the book, the pins being thus reversed from the position shown and the front cover would have 40 the sliding hinge-bar, and should it be desired to take the book apart from both ends then the binding-pins would be provided with clamping-nuts at both ends and the hinge-bars at both the front and the back of the book would have sliding connections with the cover. It is evident that other modifications may be made in the construction within 45 the purview of my invention.

50 What I claim, and desire to secure by Letters Patent, is—

1. In a book, the combination with means for detachably holding the leaves therein said means including clamping devices, of a 55 cover connected to said holding means and angularly movable relatively thereto and having a limited movement relatively thereto in addition to said angular movement independently of said clamping devices, substantially 60 as set forth.

2. A binder comprising means for detachably holding the leaves, said means including clamping devices, and a cover connected to said holding means independently of said 65 clamping devices so as to be slidably movable relatively to the holding means, substantially as set forth.

3. In a book the combination with means for detachably holding the leaves, said means including clamping devices, of an angularly-movable cover connected to said holding means independently of said clamping devices so as to be also slidably movable relatively to said holding means, substantially as set forth. 70

4. A binder comprising means for detachably holding the leaves, said means including one or more clamping devices, and a back and an angularly-movable cover, connected to said holding means so as to normally cover 80 said clamping device or devices in all positions permitted by the angular movement of said cover, said cover being also movable rearwardly to permit access to the clamping device or devices, substantially as set forth. 85

5. In a book, the combination with means for detachably holding the leaves, said means including one or more clamping devices, of a back and an angularly-movable cover connected to said holding means so as to normally cover 90 said clamping device or devices in all positions permitted by the angular movement of said cover, said cover being also slidably movable from said normal positions to permit access to the clamping device 95 or devices, substantially as set forth.

6. In a book, the combination with means for detachably holding the leaves, said means including a clamping-bar and one or more clamping devices, of a cover and a back, said 100 cover being connected to said clamping-bar at the front of said clamping-bar so that said cover and back normally cover said clamping device or devices and being movable rearwardly to permit access to the clamping device or devices, substantially as set forth. 105

7. A binder comprising means for detachably holding the leaves, said means including a clamping-bar and one or more clamping devices, and a cover connected to said clamping-bar at the front of said clamping-bar and 110 slidably movable relatively thereto, substantially as set forth.

8. A separable book comprising a clamping-bar, one or more binding-pins passing 115 through the leaves and clamping-bar, one or more clamping-nuts upon the binding pin or pins and bearing against the clamping-bar, and a cover connected to said clamping-bar in proximity to the front edge thereof so as 120 to be angularly movable and also slidably movable rearwardly relatively to the clamping-bar, substantially as set forth.

9. A binder comprising a clamping-bar, one or more binding-pins passing through the 125 clamping-bar, one or more clamping-nuts upon the binding pin or pins and adapted to bear against the clamping-bar, and a cover connected to said clamping-bar in proximity to the front edge thereof so as to be angularly movable and also movable rearwardly 130 relatively to the clamping-bar, substantially as set forth.

10. In a book, in combination, a clamping

- bar, one or more binding-pins passing through the leaves and clamping-bar, one or more clamping-nuts upon the binding pin or pins and bearing against the clamping-bar, and a cover having one or more hinge-bars hinged to said clamping-bar in proximity to the front edge thereof, said hinge-bar or hinge-bars having a sliding connection with the cover, substantially as set forth. 5
- 10 11. In a binder, in combination, a clamping-bar, one or more binding-pins passing through the clamping-bar, one or more clamping-nuts upon the binding pin or pins and adapted to bear against the clamping-bar, and a cover having one or more hinge-bars hinged to said clamping-bar in proximity to the front edge thereof, said hinge-bar or hinge-bars having a sliding connection with the cover, substantially as set forth. 15
- 15 12. A separable book comprising the clamping-bar 5, the binding-pins 6 passing through the leaves and clamping-bar, clamping-nuts 8 upon the binding-pins and bearing against the clamping-bar, and the hinge-bar 15 hinged to the clamping-bar at the front edge thereof 25 and having a sliding connection with the cover and having a shoulder to limit its sliding movement, substantially as set forth.
13. A binder comprising the clamping-bars 4, 5, the binding-pins 6 passing through said clamping-bars, the clamping-nuts 8 upon the binding-pins and adapted to bear against the clamping-bar 5, the hinge-bars 12 and 15, hinged to the clamping-bars at the front edges thereof and connected to the covers, the hinge-bar 15 having a limited sliding movement relatively to the cover, substantially as set forth. 30
- 35 Signed at the borough of Manhattan, county of New York, city and State of New York, 40 this 10th day of May, 1899.

EDWARD L. HEYDECKER.
